Primary Examiner—Doris V. Coles**Attorney, Agent, or Firm—Banner & Wicoff, Ltd.****[57]****CLAIM**

The ornamental design for a locking tube and reel seat for fishing rod handle, as shown and described.

DESCRIPTION

FIG. 1 is a perspective view of a locking tube and reel seat for fishing rod handle showing my new design;

FIG. 2 is a front view thereof;

FIG. 3 is a rear view thereof;

FIG. 4 is a side elevational view thereof, the other side being a mirror image;

FIG. 5 is a top view thereof; and,

FIG. 6 is a bottom view thereof.

The broken line showing of a fishing rod handgrip portion and blank is for illustrative purposes only and forms no part of the claimed design.
